[57] CLAIM

The ornamental design for a valve, as shown and described.

DESCRIPTION

FIG. 1 is a perspective view taken from the top, one side and one end of a valve showing my new design; FIG. 2 is an elevational view thereof taken from the side shown in FIG. 1, the opposite side being a mirror image of the side shown;

FIG. 3 is an end elevational view thereof taken in the direction of arrow 3 on FIG. 2;

FIG. 4 is another end elevational view thereof taken in the direction of arrow 4 on FIG. 2;

FIG. 5 is a top view thereof taken in the direction of arrow 5 on FIG. 2; and

FIG. 6 is a bottom view thereof taken in the direction of arrow 6 on FIG. 2.
